UNITED STATES PATENT OFFICE.

ABRAHAM GLIEBERMAN, OF BROOKLYN, NEW YORK.

HAND-BAG FRAME.

Application filed December 29, 1926. Serial No. 157,664.

This invention relates to improvements in hand bag frames, with particular reference to small bags of an ornamental nature as carried by women for articles of a personal nature, such as a purse, handkerchiefs, and minor toilet articles.

Such containers have been subject to one important disadvantage, that is, in the necessity of opening the bag to obtain access to the most frequently used article, which unquestionably is the mirror, by which the face, hair, hat and neck ornaments may be readily inspected and adjusted, if desirable.

It is therefore one of the objects to devise a bag frame having provisions whereby a mirror may become instantly accessible without opening the bag or disturbing its contents which remain in security therein.

It is a further feature to incorporate and combine with the bag frame a mirror having means for being drawn outwardly, held in any desired, adjusted position, prevented from complete extraction, or be pressed wholly within the bag to be concealed between its walls and present no uncouth or objectionable features.

These purposes, together with other minor advantageous objects which are hereinafter set forth, are accomplished by the novel construction and combination of parts described in the specification and shown in the accompanying drawing, constituting a material part of this disclosure, and in which:

Figure 1 is a partial side view of a conventional type of hand bag including a frame made in accordance with the invention.

Figure 2 is an enlarged fragmentary view showing the frame construction and supports for the mirror which is shown in its normal concealed position.

Figure 3 is a fragmentary transverse sectional view taken substantially in a plane represented by the line 3-3 of Figure 2.

Throughout the several views the numeral 5 designates in general the walls of a bag the same being made of any suitable material and in any preferred shape.

The upper edges of the walls are secured on opposite sides, in the usual manner, to the inner surfaces of a pair of opposed frame members, respectively 6 and 7, the same being of L shaped cross section, bent into a substantially U shape inverted and hinged together at their ends.

The frame member 6 has a right angle flange 6' overlying the inreaching mating

flange 7', and carrying eyes 8 in which are fixed the ends of a handle.

A snap fastener or lock 9 is provided at the center of the frames by which they are normally held together when the bag is closed, the construction throughout being of the usual type except for the improvements which will now be described.

At one side of the frame member 6' in its outer surface, is a shallow depression 10, an oblong rectangle in shape, adapted to receive a plate 11 having at its center a raised grip 12 extending above the level surface of the frame and suited to be grasped between the finger and thumb of a person in raising the plate.

Rigidly attached to the under side of the plate 11 and extending through an opening in the frame member, is the upper member of a rectangular frame 13 normally extending downwardly into the bag and having at its lower edge a pair of opposed projections 14, this frame supporting a mirror 15.

Fixed to the underside of the frame member 6' are a pair of opposed spring brackets 16 equivalent in width to the frame 13 and having on their lateral edges pairs of inreaching lugs 17 between which the mirror frame 13 is slidably guided.

The upper and lower ends of the spring brackets 16 are curved slightly outward, and their main central portions bear against the side members of the frame with sufficient friction to retain the mirror in any of its adjusted positions, while the projections 14, when the frame is extracted to its maximum extent, contact with the inner ends of the brackets.

In order to open and close the frame element 7' with respect to its mate a recess 18 is formed in its front edge to clear the frame 13 and spring brackets as best seen in Figure 3.

From the foregoing it will be understood that the mirror may be brought into operative position by grasping the extending element 12 and exerting a moderate pull without opening the bag and, as the mirror is quite thin and disposed in the upper part of the bag, between the frame elements, this can be done without disturbing the bag contents.

Although the foregoing is descriptive of the preferred embodiment of the invention, it will be apparent that minor changes may be made in its construction, without the ex-

ercise of invention or conflicting with the scope of the claim hereto appended.

Having thus described my invention, what I claim as new and desire to secure by Letters Patent, is:

In combination with a bag and a frame comprising inner and outer hinged members, the latter of which contains an open-

ing, a mirror adapted to be moved into and out of the said opening without opening the said bag and held against complete withdrawal at any desired exposed position.

In testimony whereof I have hereunto affixed my signature.

ABRAHAM GLIEBERMAN.
